UNITED STATES PATENT OFFICE.

CHRISTIAN SHARPS, OF PHILADELPHIA, PENNSYLVANIA.

IMPROVEMENT IN METALLIC CARTRIDGES.

Specification forming part of Letters Patent No. 34,987, dated April 15, 1862.

To all whom it may concern:

Be it known that I, CHRISTIAN SHARPS, of Philadelphia, Pennsylvania, have invented an Improvement in Metallic Cartridges; and I do hereby declare the following to be a full, clear, and exact description of the same, reference being had to the accompanying drawing, and to the letters of reference marked thereon.

My invention relates to an improvement in the metallic cartridge used in the French fire-arm known as Lefauchaux's revolver, which has a pin or rod at the rear of the case, and in the interior a wad in which is embedded a cap to be exploded by the rod when the latter is struck by the hammer; and my improvement consists in making the base of the casing so much stronger than other parts of the same that it will resist the shock to which it is subjected, and will retain its form after the discharge of the cartridge, the base being of sufficient thickness to allow for the formation therein of a hole for the reception of the detonating material, and the rod for exploding the same, as fully described hereafter; the object of my invention being to avoid the tedious manipulation required in constructing this class of cartridges as heretofore made, and to prevent that bulging out at the base to which they are liable, and which tends to impede the free movement of the revolving chambers.

In order to enable others skilled in the art to make and use my invention, I will now proceed to describe the manner of constructing the same.

On reference to the accompanying drawing, which forms a part of this specification—

Figure 1 is a longitudinal section of my improved cartridge. Fig. 2 is a transverse section on the line 12, Fig. 1; and Fig. 3 is a diagram illustrating the manner of perforating the rear of the cases.

The metallic case A of the cartridge is drawn from a solid disk of metal by the usual process, and is, as regards external shape, similar to that of the cartridge used in the French fire-arm known as Lefauchaux's revolver.

The metal case of the ordinary cartridge used in this weapon is of the same, or nearly the same, thickness throughout, and contains

a thick wad forces to the rear, and there cemented, the wad having a central recess in which is deposited a cap somewhat similar to those used in ordinary fire-arms, this cap being secured in its place by a metal plate. A rod or wire passes vertically through the cartridge near the base, and is so situated that when its upper end is struck by the hammer of the fire-arm, its lower end is brought in forcible contact with the detonating material in the cap, thereby igniting the powder contained in the case.

There are two serious objections to this French cartridge: First, it demands tedious and expensive manipulation. Secondly, the base of the casing being little or no thicker than any other portion of the same, is apt to become bulged out the moment the discharge takes place, and, consequently, to interfere with the free movement of the cylinder of the revolver.

I overcome both of these objections by making the base a of sufficient thickness not only to resist effectually, and without changing its form, the shock to which it is subjected when the cartridge is discharged, but also to allow for the forming of an orifice of proper dimensions for admitting the detonating material C and the rod B for discharging the same. The vertical orifice for receiving the rod communicates with a horizontal orifice, D, the detonating material C being deposited at the point where the two orifices meet. The orifice D may be readily formed by a projection or punch on the end of one of the dies used for forming the interior of the case, and the vertical orifice may be formed by drilling, or by the still more simple process illustrated in the diagram, Fig. 3, where the rear of the case is illustrated as being confined by an exterior die, E, and interior mandrel F, G being a hardened-steel pin, pointed at the end, and having a reciprocating motion imparted to it, so that it will pass through an opening in the die E and penetrate the base a of the case, the latter being made of copper or other soft metal or alloy, and form the desired orifice communicating with the orifice D. In penetrating the rear of the case the pin has necessarily a tendency to displace the metal; but as the exterior of the case is confined, this displace-

ment cannot change the external form of the case, the displacement of the metal taking place in the inside, as represented in the figure, and the internal mandrel being so formed as to permit the limited bulging out resulting from the penetration of the steel pin.

The wadding detonating cap or case, and the plate for confining the same in the casing of Lefauchaux's cartridge are thus discarded and the tedious manipulation required in adjusting and securing the same is avoided; at the same time the base, *a*, is sufficiently thick and rigid to resist the shocks to which it is subjected, and to prevent that bulging out of the rear of the case which takes place in Lefauchaux's cartridge, and which, as before remarked, interferes with the free movement of the revolving cylinder of the fire-arm.

I do not desire to claim, broadly, a cartridge in which the powder is ignited by means of detonating material exploded by a pin pass-

ing transversely through the rear of the cartridge; but

I claim as my invention and desire to secure by Letters Patent—

The metallic cartridge-case composed of the hollow cylinder *A*, with a base, *a*, of such a strength as to effectually resist the shock to which it is subjected, and of such a thickness that an orifice may be formed in the solid metal of the base for the reception of the detonating compound, and a rod or wire for exploding the same, as herein set forth, for the purpose specified.

In testimony whereof I have signed my name to this specification in the presence of two subscribing witnesses.

CHRISTIAN SHARPS.
